COMBINED CANDLE AND STAND

Henrietta T. Gardner, 6903 Armat Drive,
Bethesda, Md. 20014

Filed May 31, 1966, Ser. No. 2,466

Term of patent 14 years

(Cl. D48—2)

FIG. 1 is a front perspective view of a combined candle and stand, showing my new design;

FIG. 2 is a rear elevational view thereof; and

FIG. 3 is a sectional view taken along section line 3—3.

The flame shown in broken lines in FIG. 1 is for illustrative purposes only.

I claim:

The ornamental design for a combined candle and stand, as shown and described.
